Primary Examiner — Deanna L Pratt*Assistant Examiner* — Katie Mroczka(74) *Attorney, Agent, or Firm* — Wood, Herron & Evans, LLP(57) **CLAIM**

The ornamental design for a monitor, as shown and described.

DESCRIPTION

FIG. 1 is a top front perspective view of a monitor showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the monitor which form no part of the claimed design.

1 Claim, 4 Drawing Sheets(63) Continuation-in-part of application No. 29/434,700, filed on Oct. 16, 2012, which is a continuation-in-part of application No. 29/425,734, filed on Jun. 26, 2012, now Pat. No. Des. 682,271.
